INVENTOR.

Eben Denton

United States Patent Office.

EBEN DENTON, OF BRAINTREE, MASSACHUSETTS.

Letters Patent No. 105,554, dated July 19, 1870.

IMPROVEMENT IN SHIPS' TOPMASTS.

The Schedule referred to in these Letters Patent and making part of the same.

To all persons to whom these presents shall come:

Be it known that I, EBEN DENTON, of Braintree, in the county of Norfolk and State of Massachusetts, have invented a certain new and useful Improvement in Raising and Lowering Topmasts; and that the following is a full and exact description of the same, reference being had to the accompanying drawing.

The present invention consists—

First, in arranging a topmast to be raised and lowered by and through an endless rope or line to which the topmast is connected.

Second, in combination with the above, arranging the topmast to be guided on the said endless rope in its movement up and down; and

Third, in an arrangement of locking mechanism for securing the topmast in position to the mainmast when raised.

In the accompanying drawing my improvement in raising and lowering topmasts is illustrated—

Figures 1 and 2 being views, in elevation, from different sides, with the topmast and mainmast broken off, to the more fully show the features of the present invention.

Figures 3, a transverse section in plane of line x x , fig. 2.

Figure 4, a view in detail of the top and mainmasts, with the topmast down.

A, in the drawing, represents a mainmast, secured to and in deck B, and

C, the topmast.

D, a ring or cap, applied to upper end of mainmast, with its loop E projecting therefrom, through which the topmast plays and moves.

F and G, pulleys; the one, F, secured to mainmast A, near its upper end, and the other, G, in the present instance shown as arranged below the deck B, turning in bearings of a frame, H, arranged as will be hereinafter described.

I, an endless rope passing around pulleys F and G, up and down along the length of the mainmast, through holes in the deck or floor B.

J, a ring fastened to mainmast just below pulley.

This ring J is provided with eyes K, through which the rope I passes, and is constructed with a spring-catch, L, in its dovetail recess M, for the purpose of locking the topmast, when up within said recess, by the tongue O, applied to mainmast.

P, a lever hung to mainmast, for relieving the spring catch from the tongue O of the topmast, when desired to lower it, the said lever being operated from the deck by and through the rope P².

Q, a cap applied to lower end of topmast, and, by its eyes R, is arranged on the endless rope, being at one side, S, tied to the same, so that, in the running of the rope, the topmast will be moved up and down and at its other side let loose on the rope, whereby it is guided and steadied in its motion.

The lower pulley is provided with a winch-handle, T, for convenience in turning it to run the rope; and, to hold the pulley from turning backward after the topmast is raised, a ratchet and pawl, U, are arranged in connection with the pulley.

To produce tension on the rope, the frame H, in which the lower pulley G is hung, is, by means of a screw-shaft, V, attached thereto, arranged to be moved up and down, being guided and steadied by the arm X, arranged to play in the slotted uprights Y of the frame H, fixed to the under side of the deck or floor B.

By the arrangement of the mechanism above described, the topmast can be raised and lowered at pleasure, and without being obliged to mount the mainmast, the topmast, as is obvious, being run up and down by the endless rope, and on it guided and steadied.

Having thus described my invention,

What I claim, and desire to secure by Letters Patent, is—

1. A topmast, arranged to be raised and lowered through an endless rope or line, substantially as and for the purpose described.

2. In combining with the above the topmast arranged to be guided on the said endless rope or line, substantially as and for the purpose set forth.

3. The spring catch L, or its equivalent, applied to the main and topmasts, substantially as and for the purpose described.

The above specification of my invention signed by me this 29th day of April, A. D. 1870.

EBEN DENTON.
